RAILROAD TIE

Filed April 15, 1930

FIG. 2.

WILLIAM H. EMPRY. INVEN

BY Martin & Rendell

ATTORNEYS

UNITED STATES PATENT OFFICE

WILLIAM H. EMPEY, OF FORESTPORT, NEW YORK

RAILROAD TIE

Application filed April 15, 1930. Serial No. 444,573.

My present invention relates to a composite railroad tie.

The purpose of this invention is to provide a new and improved form of composite railroad tie; that is a tie wherein is combined a metallic tubular body and one or more wood or fibrous portions therewithin to receive the railroad spikes.

A further purpose of the invention is to provide a tie of the character designated 10 wherein the tubular body is strong and rigid when assembled and particularly is of such construction that the railroad rails may be readily but very securely fastened thereto and positively held in position longitudinally of 15 the tie.

A further purpose is to provide a tie of 20 this type wherein one layer of the metal of the tubular body is provided upon the top of the wooden core and beneath the rail and another layer on the top of the metal body is provided to extend along the opposite edges of the rail base so as to positively position the rail against lengthwise movement upon the tie; and further preferably to have one 25 or two of the sides of the body adjoining the upper layer of the body pass immediately below the rail at the sides of the tie so as to hold the upper or outer layer of the two top 30 layers in place firmly against the inner layer and so as to aid in distributing the strain of weight and use over a large part of the tie and onto a considerable portion of the wooden or other core.

35 Further purposes and advantages of the invention will appear from the specification and claims herein.

Fig. 1 is an isometric view of a composite tie embodying my invention with one rail in 40 place thereon.

Fig. 2 is a vertical longitudinal section through a part of said tie and one of the rails thereon.

Fig. 3 is a transverse sectional view through 45 the tie and a side elevation of the rail on line 3—3 of Fig. 1.

Fig. 4 is a transverse sectional view similar to Fig. 3 of a modified form of tie and Fig. 5 is a similar view of another modification of the tie.

Referring to the drawings in a more particular description it will be seen that the composite railroad tie here shown comprises a wooden or other fibrous core 8 and a metallic tubular body 9 placed thereabout. The core 8 is nearly the height and width of the 55 complete tie and may be in the form of a short section underneath each rail 10 as shown in Fig. 2 or it may be the full length of the tie or at least long enough so that one such wooden or fibrous section reaches beneath 60 both of the rails 10.

The metallic tubular body 9 is preferably formed of sheet metal of the desired character and thickness by bending or otherwise forming the sheet of metal four or five times 65 so as to form a substantially rectangular tube consisting of the bottom 11 and opposite upstanding sides 12 and 13 and two top layers 14 and 15. Said two top layers overlap closely with the layer 14 being the inner one and the layer 15 the outer one, that is on top of the layer 14. The tube thus formed is of a size to admit therewithin the core or block 8 of wood or other fibrous material. Conveniently the said core is inserted from either 75 open end of the metallic body. The body and core when assembled fit each other relatively closely both laterally and vertically.

In all forms of the construction the outer 80 top layer 15 of the body is cut away or otherwise formed with railbase-receiving apertures 16 at the points in the tie where the rail 10 is to be located. This railbase-receiving aperture extends longitudinally of the 85 tie for the width of the railbase 10^a and extends transversely of the rail for the full width of the said outermost top layer 15.

This aperture allows the bottom of the railbase 10^a to rest flat down upon the upper 90 surface of the inner top layer 14 of the metallic body and this innermost layer 14 in turn rests flat against the top of the wooden block or other fibrous core 8 which in turn at its bottom rests upon the bottom 11 of 95 the metal body. It will be seen that as far as the parts so far mentioned, this obtains a strong direct distribution of the weight and strain of use through both the metal body and the wooden core. By having the railbase 100

10^a rest flat upon the innermost top layer 14 wear and cutting away of the tie by pressure from the rail is avoided.

In all forms of my construction the cutting or forming of the rail-receiving aperture 16 leaves two oppositely spaced vertically extending edges 17 and 18 upon the outer layer 15 which edges form shoulders to engage the opposite upright edges 10^b and 10^c of the railbase 10^a. By placing these rail-receiving apertures accurately in the proper longitudinally spaced positions upon the tie and making the width of such apertures correspond as closely as practicable to the width of the rail base 10^a, the said shoulders 17 and 18 of the said outer upper layer 15 not only aid in originally positioning the rails in the right place relative to the tie, but when the rail is fastened to the tie by the usual spikes 19 practically all of the side strain from the rails is taken into the tie through said outer layer instead of simply against the upper part of the spikes 19.

It will be understood that adjacent the side edges of the rail 10 there are provided spike openings 20 in the outer top layer 15 and registering therewith similar holes extending through the inner top layer 14. These holes are made as close as may be in size to fit the spikes 19 and the sides of the hole away from the railbase further act to press and reinforce the head and upper end of the spikes 19 so that the spikes are relieved still further from strain that would otherwise be placed thereupon.

In the preferred form of my construction as shown in Figs. 1 to 3, the outermost top layer 15 does not terminate at the upper right hand edge of the tie as viewed in Figs. 1 and 3, but is provided with a downwardly extending side wing 21 which overlaps on the outside a considerable portion of the right hand side 13 of the metal body. This wing operates to connect the said outer top layer 15 beyond the rail-receiving aperture 16 and provides a horizontal shoulder 22 at the right side of the tie as viewed in Fig. 3. This shoulder and the corresponding shoulder 23 in the lefthand upright side 12 are close beneath the railbase 10^a when the rail is fastened in place upon the tie. The engagement of the railbase with the shoulder 22 tends to keep this side of the outer top and layer 15 closely down against the inner top layer 14 and by reason of the rail engaging the vertically arranged web 21 the strain or weight of the rail upon this side of the tie is distributed back onto the said outer top layer 15. In a similar way the strain or weight of the rail resting upon the shoulders 23 is taken first upon the vertical web formed by the left hand side 12 and therefrom is distributed to the outer top layer 15 and also to the bottom of the tie 11.

In the modifications shown in Figs. 4 and 5

the downwardly depending wing 21 is omitted. As shown in Fig. 4 the outermost top layer 15 is of the full width of the tie. In the modification shown in Fig. 5 the outermost layer 15 is of less width than the width of the tie but still provides ample extent for the upstanding shoulders 17 and 18 to make good engagements with the side edges of the rail base 10^a. The forms shown in Figs. 4 and 5 use some less metal and form a sufficiently strong tie but are not so nearly waterproof as the forms shown in Figs. 1 and 3.

What I claim as new and desire to secure by Letters Patent is:

1. A railroad tie comprising a fibrous spike-receiving block below the rail and a metal tubular body bent about said block and having two overlapping top layers, the upper of said top layers being provided with a railbase-receiving aperture extending the full width of the said layer and extending lengthwise of the tie for the width of the railbase whereby the rail may rest upon the upper surface of the inner of the said top layers and the upper layer's aperture edges extending crosswise of the tie form spaced upstanding shoulders engaging the opposite sides of each railbase.

2. A railroad tie comprising a fibrous spike-receiving block below the rail and a sheet metal tubular body bent about said block and having two overlapping top layers, the upper of said top layers being provided with a railbase-receiving aperture extending the full width of the said layer and extending lengthwise of the tie for the width of the railbase whereby the rail may rest upon the upper surface of the inner of the said top layers and the upper layer's aperture edges extending crosswise of the tie form spaced upstanding shoulders engaging the opposite sides of each railbase.

3. A railroad tie comprising a fibrous spike-receiving block below the rail and a metal tubular body bent about said block and having two overlapping top layers, the upper of said top layers being provided with a railbase-receiving aperture extending the full width of the said layer and extending lengthwise of the tie for the width of the railbase whereby the rail may rest upon the upper surface of the inner of the said top layers and the upper layer's aperture edges extending crosswise of the tie form spaced upstanding shoulders engaging the opposite sides of each railbase, the upstanding side parts of the body adjoining the upper top layer passing immediately below the railbase and being engaged thereby whereby the outer top layer is held down and weight is distributed.

4. A railroad tie comprising a fibrous spike-receiving block below the rail and a sheet metal tubular body bent about said block and having two overlapping top layers,

the upper of said top layers being provided
with a railbase-receiving aperture extending
the full width of the said layer and ex-
tending lengthwise of the tie for the width
5 of the railbase whereby the rail may rest
upon the upper surface of the inner of the
said top layers and the upper layer's aper-
ture edges extending crosswise of the tie
form spaced upstanding shoulders engaging
10 the opposite sides of each railbase, the up-
standing side parts of the body adjoining the
upper top layer passing immediately below
the railbase and being engaged thereby
whereby the outer top layer is held down and
15 weight is distributed.

In witness whereof I have affixed my signa-
ture this 31st day of March, 1930.

WILLIAM H. EMPEY.
